UNITED STATES PATENT OFFICE.

FREDERIC STILES, OF BINGHAMTON, NEW YORK, ASSIGNOR, BY DIRECT AND MESNE ASSIGNMENTS, OF THREE-FIFTHS TO RUFUS K. ALLERTON AND CHARLES H. HALL, OF SAME PLACE.

CIGAR-WRAPPING MACHINE.

SPECIFICATION forming part of Letters Patent No. 496,453, dated May 2, 1893.

Application filed April 8, 1892. Serial No. 428,337. (No model.)

To all whom it may concern:

Be it known that I, FREDERIC STILES, a citizen of the United States of America, residing at Binghamton, in the county of Broome and 5 State of New York, have invented certain new and useful Improvements in Cigar-Wrapping Machines, of which the following is a specification, reference being had therein to the accompanying drawings.

10 In a machine for wrapping and finishing cigars it is desirable that the rollers should be adapted to conform to the shape of the cigar operated upon, and should be adjusted to different sizes and shapes of cigars; mechanism should be provided by means of which 15 the wrapper may be fed evenly and without wrinkling; and that the machine should also finish the cigar by completely wrapping the head without requiring special hand labor for 20 that purpose. Further, it is desirable that the machine should be so constructed that it may be opened to receive the bunch and the stopping and starting also should be controlled by a treadle so that the hands of the 25 operator may be left free to manipulate the material. It is also desirable in some cases to provide a machine capable by adjustment and by replacing some of the parts to wind either right hand or left hand wrappers. In 30 the machine hereinafter described and in which my invention is included I have sought to accomplish these objects and I have hereinafter set forth the particular constructions and combinations in which my invention consists. 35

The machine is illustrated in the accompanying drawings, in which:—

Figure 1 shows a rear elevation of the machine. Fig. 2 represents a plan view of the 40 machine. Fig. 3 shows a section on line $x-x$ of Fig. 2. Fig. 4 is a longitudinal section of one of the rollers. Figs. 5, 6 and 7 are perspective views of details.

In the drawings, A, A' represent the end 45 pieces of the frame of the machine.

A' is a plain casting in the form of a standard in which the rods or bars B are fixed connecting it to the end piece A, and in which also are the bearings of the various shafts.

It is provided with a horizontal slot in which 50 is located the block a, forming the bearing of the left hand end of the shaft b; this block slides in the slot and is provided with a stem extending lengthwise of the slot through a cap piece c. The end of it is threaded and is 55 provided with a nut d having a milled head. A coiled spring e, is placed on the stem one end bearing upon the cap and the other end upon the block so as to hold the block normally pressed against the inner end of the 60 slot. By means of the nut the bearing block may be turned to the front against the pressure of the spring in order to adjust the shaft b. The end piece A has a similar slot provided with a block, stem, spring and nut 65 marked by the same letters. By means of these either end of the shaft b, or both, may be adjusted in horizontal directions. The shaft b, carries one of the rollers by which the cigar is held and turned. The main roller is 70 upon the shaft f, which has fixed bearings in the end pieces A, A'. The right hand end is provided with a pinion h, which meshes into a pinion i on the driving shaft I. This shaft is mounted in bearings in an extension 75 A' of the part A, these parts being preferably cast in one piece. The shaft is provided with a loose wheel k, which may be held to the shaft by means of a clutch l, splined on the shaft and mounted in the upper end of a bell 80 crank lever m, pivoted on the extension and movable by connections with the treadle. The shaft b is driven by a pinion b' meshing 85 with the pinion on the shaft I. The vertical slot of the screw 3 is shown in Fig. 2. The position of the screw 4 is shown in Fig. 3, and the vertical slot is in part shown above the screw. The third roller is on the shaft g, which is mounted in a swinging frame, and this shaft has a pinion g' also in mesh with 90 the pinion i when the machine is in working position. The shaft g is mounted in a frame H; the bearings in which it turns are vertically adjustable on this frame. These bearings are marked 1 and 2 and their lower extensions are held by set screws 3, 4, in vertical slots in the frame so that they may be 95 slightly raised or lowered on the frame H.

The bearing 2 has an arm 6 extending laterally and carrying a third bearing to support the shaft *g* the end of which carries the pinion.

5 The frame *H* has pivoted sockets 7 and 8 on its lower part, which are pivoted upon rods *m*, *n*, set adjustably in holes in the end pieces and held by set screws 9 and 10. The frame *H* rocks on these rods so as to move the roller 10 upon the shaft *g* toward or from the cigar when the latter rests on the roller on main shaft *f*. This movement may be for the purpose of adjustment, or, when carried to its full extent for the purpose of opening the machine to receive the bunch or to drop the finished cigar. To effect these movements and to regulate the normal position of the roller, I have provided an arm 13 on the frame *H* in which is a regulating screw 14 arranged to 15 bear on a stud 15 set in the end piece *A'*. This regulating screw has a jam nut 16 to hold it securely in place. The frame is normally held inward by a spring 17. Another arm 18 on the frame *H* is provided with connections which lead to a treadle similar to that which releases the clutch of the driving wheel so that the machine may be arrested by one treadle and opened by the other.

It will be observed from the description 20 above given of the frame *H* and its connection, that it may be shifted laterally, and to permit this the pinion *g'* is held on the shaft *g* by a set screw, so that when the frame *H* is shifted in that direction the shaft may pass 25 through the pinion without displacing it. This adjustment laterally is required when the apparatus is changed from a right hand winding to a left hand winding as hereinafter more fully explained.

30 The rollers on the shafts heretofore explained, are marked respectively *B* and *F* and *G*. They are arranged coterminously, and the two upper (*B* and *G*) in such relation to each other and to the lower on which the bunch rests, that it is held in the grasp of the rollers, and is turned as they revolve, and in the turning the wrapper is wound upon the bunch.

The particular construction of the rollers 35 is hereinafter described. To secure the even and unwrinkled application of the wrapper (which is of prime importance), I provide a feed plate having a guiding edge, fitted to guide the wrapper to the bunch. This edge 40 is therefore inclined to the axis of the bunch, as it lies in the grasp of the rollers. The plate is shown at *P*. Its front rests upon the flange *p* of a bracket *q*, held on a bar *Q* which is supported upon the end pieces *A*, *A'*. The 45 feed plate is curved as shown in the sectional view Fig. 3, and is held to the bracket by set screws set in the bracket and passing through slots in the feed plate said slots being in line of movement to and fro the rollers. The 55 fit of the set screws in the slots is loose so that the feed plate may be adjusted more or

less at either end, to conform to the particular shape of the cigar operated upon. The plate curves over the roller *B* and down close to it, but not in contact with it.

70 In the drawings the machine shown is arranged for right hand winding.

The left hand end of the plate which is opposite the tuck end of the cigar, is farthest back, and does not, in the form shown, extend quite over the roller *B*. It inclines forward toward the right to follow the taper of the cigar toward the head thereof. The guiding edge is rounded and is approximately in the form of a rib, the plate in front of the rib 80 being depressed, so that the wrapper, as it is drawn over the rib or edge bears upon it alone, and does not bear upon the plate in front of the rib.

The incline of the guiding edge is designed 85 to be approximately at right angles to the line of the wrapper in the process of wrapping the bunch. At the most advanced end of the feed plate, which in the form shown, is the right hand end, is an arm *R* carrying the 90 header *r*. This arm is held to the bracket by a set screw passing through slots in the arm of the bracket into the bar. The bracket at the other end is also held by a slotted connection so that it may be adjusted laterally 95 and held in place by the set screws. The arm *R* lies up against the plate and is flush with its upper surface forming practically a continuation of the plate, and the guiding edge is prolonged in the form of a finger as shown 100 at *U*, over the front and downwardly turned end of the arm just above the header. The header has a cone shaped cavity fitted to receive the head of the cigar; it is open on the upper side and the front face of the arm 105 curves continuously down into the cavity of the header. The lip on the opposite side is curved down, with a groove *t* extending from the tip of the header cavity down to the end of the header. The end of the guiding edge 110 which projects from the arm and above the header cavity is curved down also so that the fingers of the operator, pressing upon the tip of the wrapper may follow it and retain the touch upon it quite down to the cavity, and 115 by this construction the operator is enabled to guide the wrapper close down to the header cavity where it is received, and by the cavity itself accurately wrapped upon the head, as the wrappers are cut by suitable dies to fit 120 the size and shape of the bunch operated upon.

The mechanism above described completes the wrapping and finishes the cigar with accuracy and certainty.

125 As has been explained, the guiding edge and the rollers *B* and *G* may be adjusted accurately to conform to the shape of the bunch to be wrapped. The wrappers having some elasticity may be held over the guiding plate and permitted to move over the guiding edge 130 perfectly smooth, and may be laid upon the bunch without wrinkling, even if the guiding

edge be not accurately parallel with the side of the cigar; but it is designed to conform substantially in its inclination to the shape of the cigar, and the extended part which projects across the face of the arm and over the header continuously guides the wrapper to the tip.

In changing the machine from a right to a left hand wrapper, the arm and the feed plate 10 are removed and another arm and feed plate supplied exactly like those described excepting that they are in reversed form.

The frame H has a bearing plate 20 below its lower end upon which is supported a wiper 15 U. This wiper consists of a plate 21 slotted centrally from front to rear and held to the plate 20 by a set screw. The front edge is formed with an upwardly turned flange 22, the upper edge being slightly curved and the 20 face made smooth and slightly rounded to bear gently against the side of the bunch and to smooth the wrapper as it is wound upon the bunch. Being held by a single screw it may be moved forward and turned so as to 25 conform accurately to the shape of the bunch, and when adjusted properly upon the plate 20 it is carried by the frame, and the amount of pressure applied to it by the spring is regulated by the adjusting screw which regulates 30 the frame H.

The rollers consist of flexible sleeves preferably of rubber, or some of its compounds which are held upon the shafts by means of thimbles 25. These have upon them collars 35 26 and the ends of the thimbles are inserted into the ends of the roller sleeves 28 being fitted to hold the roller sleeves by frictional contact. The thimbles are set adjustably upon the shafts and held by set screws so that 40 by pressing them together or extending them the shape of the roller may be modified. As the rubber fits tightly over the thimbles the air is held therein and a free yielding roller is produced. Upon the shaft b, is set a 45 tightly fitting supplemental tapering roller or spool 28^a which may be slid into or out of place. When it is brought into place it is in position to bear upon the tuck end of the cigar. This is used when the tuck end is extended 50 and reduced. The extended tuck end would rest upon the other side upon the supplemental roller or spool 29 on the shaft f.

It will be observed that in Fig. 4 the front roller B is placed in a lower plane than the 55 rear roller G and that the feed plate is also lower and does not cover the space between these two rollers. This arrangement while it does not interfere with the gripping of the rollers upon the bunch at the same time 60 permits the operator to see the cigar in the process of wrapping, so that if he should fail properly to lap the wrapper, he can arrest the machine by motion of his foot and readily correct the mistake. The pinions on the ends 65 of the adjustable shafts are formed with teeth

of sufficient depth to allow the required movement of adjustment without losing the mesh.

The bunch rests on the roller F with its end on the supplemental roller on the same shaft. The roller B rests against the front side, and the roller G on the rear, a little above the center. The bunch is thus held in the grip of the rollers, but with the upper side exposed. In the machine as shown, the rollers turn in the direction of the arrow. The 75 wrapper folded and tucked on the tuck end, the bunch placed, and the machine started, it rolls the bunch into or upon the wrapper, after the manner of hand wrapping, and the 80 wrapper is guided and smoothed in its application to the bunch by the guiding edge. Each fold or wrap, as it is formed, is also smoothed and pressed by the wiper, as the bunch turns up on the other side but the head of the wrapper is thus smoothed and 85 pressed by the cavity of the header which is made to conform to the shape of the bunch, and may be removed when the form of bunch is changed.

I claim as my invention—

1. In a cigar wrapping machine and in combination a lower roller arranged to support the bunch, a front roller mounted on horizontally adjustable bearings, and a rear roller mounted on a swinging frame, the front and 90 rear rollers being arranged to grasp the bunch on each side, substantially as described.

2. In a cigar wrapping machine, and in combination, a lower roller arranged to support the bunch, an upper front roller mounted on 100 horizontally adjustable bearings, and an upper roller mounted in a swinging frame normally pressed toward the front roller, and an adjustable screw and bearing therefor, whereby the rear roller is also made adjustable, 105 substantially as described.

3. In a cigar wrapping machine and in combination, a lower roller arranged to support the bunch, upper rollers combined with 110 springs and arranged to grasp and turn the bunch, and a feed plate having its edge next to the rollers, inclined to a vertical plane parallel with the axes of said rollers, and substantially at right angles to the line of feed, substantially as described.

4. In a cigar wrapping machine and in combination, a lower roller arranged to support the bunch, the upper rollers combined with springs and arranged to grasp and turn the bunch, and a feed plate having its edge next 120 to the rollers inclined to a vertical plane parallel with the axes of said rollers and substantially at right angles to the line of feed, the said plate having a groove in front of its edges, substantially as described.

5. In a cigar wrapping machine, a set of rollers arranged to grasp and turn the bunch, and a feed plate having an inclined edge, a header, and a finger, the said finger projecting over the header, substantially as described. 125 130

6. In combination with the rollers of a cigar wrapping machine, a header having an upper opening and a curved lip combined with a guiding plate for the wrapper having a finger extension of its edge projecting over the upper opening of the header, substantially as described.
7. In combination with the adjustable rollers of a cigar wrapping machine an adjustable wiper consisting of a plate having an edge arranged to bear against the bunch, and to press upon the wrapper, substantially as described.
8. In a cigar wrapping machine a roller, mounted on a swinging frame, an adjustable
- wiper plate mounted thereon, and arranged to bear upon the bunch, and means for adjusting and moving said frame, substantially as described.
9. In a cigar wrapping machine a set of rollers arranged to grasp and turn the bunch and a feed plate having a guiding edge adjustable at either end to conform to the shape of the bunch to be wrapped.
- In testimony whereof I affix my signature in presence of two witnesses.

FREDERIC STILES.
